UNITED STATES PATENT OFFICE.

HAROLD D. ARNOLD, OF EAST ORANGE, NEW JERSEY, ASSIGNEE, BY MESNE ASSIGNMENTS, TO WESTERN ELECTRIC COMPANY, INCORPORATED, A CORPORATION OF NEW YORK.

MANUFACTURE OF VACUUM-TUBE DEVICES.

1,297,309.

Specification of Letters Patent. Patented Mar. 18, 1919.

Application filed November 18, 1915. Serial No. 62,259.

To all whom it may concern:

Be it known that I, HAROLD DE FOREST ARNOLD, a citizen of the United States, residing at East Orange, in the county of 5 Essex and State of New Jersey, have invented certain new and useful Improvements in the Manufacture of Vacuum-Tube Devices, of which the following is a full, clear, concise, and exact description.

10 This invention relates to the manufacture of vacuum tube devices, and more particularly it relates to a method of exhausting air and other gases and vapors from the glass bulbs or containers which inclose the electrode elements of thermionic repeaters, such as audions, and similar devices in which extremely high vacua are desired.

Its objects are an effectively complete elimination of the gases occluded by the 20 walls of the containing vessel, and by the electrode elements and other metallic surfaces inclosed therein, a removal of such gases or any other gases from the containing vessel, and a resulting product characterized by stability and uniformity of operation.

To these ends this invention provides for the attachment of the vessel to be exhausted to any suitable vacuum pump and for the 30 application of heat to the exterior of such vessel during the process of evacuation. It further provides for the heating of one or more of the inclosed electrodes by the passage of an electric current therethrough, and 35 for the production in said vessel of an electron discharge which may be made to bombard and heat another electrode through the application of a suitable potential difference between the said electrode and the source of 40 said discharge.

A more complete understanding of the method of this invention will be obtained by consideration of the attached drawing, which illustrates an apparatus arrangement 45 suitable for producing the high vacua desired in thermionic devices of the audion type. It will, of course, be appreciated that the method herein disclosed is equally applicable to the production of high vacua in any 50 device having an electrode or electrodes capable of producing an electron discharge.

In the drawing, a plurality of thermionic repeater elements 2, each having the customary filamentary cathode 3, grid 4 and anode

5, are inclosed in an oven 6 which may be 55 electrically heated by a resistance element 7 connected to a suitable source of current 8. The glass containing vessels 9 of the elements 2 have tubular extensions 10 connected to a main tube 11 leading to an exhaust apparatus 12, such, for example, as a Gaede molecular pump, connected to a source of motive power 13. The terminals of the electrode elements 3, 4 and 5 are brought out through suitable apertures 14 in one of the 60 walls of the oven 6, so as to be readily available for test purposes and for the application of any desired electromotive force. A suitable number of windows 15 are provided in the front of the oven 6 so that the appearance of the tubes 2 being exhausted may be 65 observed during the process. The filaments 3 are connected in series with a source of current 16 and a variable resistance 17. The process of exhausting the vessels 9 is as follows: The pump 12 is started and the temperature of the oven 6 is gradually raised until it has reached approximately 350° C. The purpose of this heating is to drive out 70 the gases occluded by the walls of the vessel 80 9. After the temperature of the oven has risen to about 250° C., the filaments 3 are brought to incandescence by current supplied from the source 16, which current is raised to a value approximately 10% greater than 85 the current normally to be used in the operation of the completed device. A potential difference is thereupon successively applied to the terminals of the electrodes 4 and 5 by means of a test clip 20 connected through 90 the potentiometer 21 to a direct current source 22 of about 220 volts output. The filament 3 being connected to the negative terminal of the source 22 as shown, and the test clip 20 being connected to the positive 95 terminal of the source 22, there will result an electron discharge from the cathode 3 to the electrode 4 or 5, to which the test clip 20 is temporarily connected. This potential difference is made sufficiently high, through adjustment of the potentiometer 21, to cause 100 an electron discharge of sufficient volume to heat the electrode, to which the test clip 20 is attached, even to incandescence, which heating is effective to drive out any gases 105 which may be occluded by said electrode.

The electron discharge, which passes from the cathode 3 to either electrode 4 or 5 when

a potential difference is established there-between, partially ionizes whatever gas may be in its path. When gas in sufficient quantity is thus ionized, there will result a blue 5 glow in part or all of the vessel 9, which may readily be observed through one of the windows 15. The intensity of this blue glow depends upon the amount of gas present and upon the current and potential difference 10 impressed between the cathode 3 and electrode 5. For a given current and potential difference therefore, this blue glow will gradually become fainter as the gas within the vessel becomes more attenuated, until 15 the glow finally disappears.

A visible indication of the sufficiency of evacuation is therefore available, and, for example in exhausting the bulbs of thermionic repeaters, such as are employed in telephone work, it has been found that a sufficiently high vacuum has been obtained if the blue glow no longer appears, when approximately 175 volts potential difference is impressed between the cathode 3 and the anode 20 5. When this point has been reached, the tubes are allowed to cool gradually and are sealed off of the pump 12 and given an aging run, which consists in applying the normal heating current to the filaments 3 and im- 25 30 pressing the customary operating potential difference between the cathode 3 and anode 5. It has been found that after an aging run of from fifteen to twenty hours duration, for example, the repeaters have reached 35 a stable condition and may be relied upon to give constant and uniform results.

In case the thermionic device to be exhausted is equipped with a grid 4 of very fine mesh, as in the case of a repeater de- 40 signed for voltage amplification, it may be difficult to obtain a current to the electrode 5 sufficient to heat it properly. In such an event, it has been found desirable to apply an additional positive potential from a 45 source 23, for example of perhaps 60 volts output, to the grid electrode 4 at the same time that the positive potential from source 22 is being applied to the anode 5. This increases the flow of electrons to the anode 5, 50 and as some current will also flow between the filament 3 and grid 4, the voltages may

be adjusted so as to heat both electrodes 4 and 5 at the same time.

With some tubes the early part of the process may be accelerated by applying to 55 both the grid electrode 4 and the anode 5 the same large potential as that which later in the process is applied to the anode only.

What is claimed is:

1. The method of producing a high vacuum in a thermionic discharge tube containing three electrodes, which comprises heating one of said electrodes and establishing an electron discharge between said heated electrode and a second one of said electrodes, whereby said second electrode is heated during the process of evacuation, and in assisting the passage of said discharge by means of a potential difference applied between the source of said discharge and the third electrode. 60

2. The method of producing a high vacuum in a thermionic discharge tube containing three electrodes, which comprises heating one of said electrodes to cause it to 75 emit electrons, in establishing an electron discharge between said heated electrode and the other two electrodes during the process of evacuation, whereby said two electrodes are heated by bombardment and their oc- 80 cluded gases are driven off.

3. The method of evacuating a vacuum tube having cathode, anode and grid electrodes, which comprises energizing said cathode to cause it to emit electrons, in es- 85 tablishing an electron discharge between said cathode and said other electrodes during the evacuation, and in maintaining said grid at a potential different from that of said cathode during said discharge. 90

4. The method of evacuating a vacuum tube having cathode, anode and grid electrodes, which comprises energizing said cathode to cause it to emit electrons, and in maintaining said grid and anode at a positive potential with respect to that of said cathode during evacuation. 95

In witness whereof, I hereunto subscribe my name this fifteenth day of November, A. D. 1915.

HAROLD D. ARNOLD.
